UNITED STATES PATENT OFFICE.

HENRY S. PRENTISS, OF ELIZABETH, NEW JERSEY, ASSIGNOR TO THE PRENTISS CLOCK IMPROVEMENT COMPANY, OF NEW YORK, N. Y., AND JERSEY CITY, NEW JERSEY.

SYNCHRONIZER FOR CLOCKS.

SPECIFICATION forming part of Letters Patent No. 533,919, dated February 12, 1895.

Application filed June 30, 1892. Renewed June 22, 1894. Serial No. 515,425. (No model.)

To all whom it may concern:

Be it known that I, HENRY S. PRENTISS, a citizen of the United States, and a resident of Elizabeth, in the county of Union and State 5 of New Jersey, have invented certain new and useful Improvements in Synchronizers for Clocks, of which the following is a specification.

My invention has reference to electrically 10 synchronizing clocks having self contained motors, and it consists in certain novel features, whereby slow running clocks are advanced to the correct time at the commencement of the synchronizing period, and fast 15 running clocks are held at the hour, until the exact hour as indicated by the master clock is reached, or until the end of the synchronizing period; all of which is more fully pointed out in the following specification and claims, 20 and illustrated in the accompanying drawings, in which—

Figure 1 represents a face view, part being broken away, of a secondary clock. Fig 2 is a vertical section in the plane $\alpha\alpha$, Fig. 1. 25 Fig. 3 is a diagram showing the arrangement of the clocks in a system. Figs. 4 to 9 are detail views on a larger scale than the preceding figures, illustrating detail parts and their operation.

Similar letters indicate corresponding parts throughout the several views.

In these drawings the letter C designates one of the secondary clocks, which may embody any suitable motor and movement. 35 In this example, I have illustrated a pendulum movement, in which m is the arbor of the minute hand; P , the pendulum; V , the verge rod; p , the pallet lever mounted on an arbor p' , and S , the scape wheel mounted on 40 an arbor j .

In line with the arbor j , (see Figs. 4 to 9 especially) and supporting one end thereof, is arranged a stud j' , on which is mounted a pinion g which is adapted to slide back and forth thereon, and meshes with one of the gears of the train. The pinion carries a dog 45 $a\ b$, one end a of which is provided with a tooth a' , normally adapted to engage with one of the teeth of the scape-wheel S for propelling the same. The opposite end b of the dog is arranged to be engaged, under certain cir-

cumstances, by a detent c secured to the frame of the clock. The pinion g is engaged by a forked arm g' mounted on a bar g^2 , which is guided to move in the direction of its length 55 and is connected to the armature f of an electromagnet M . A spring h normally draws the pinion toward the scape-wheel, its motion being arrested by a suitable shoulder on the bar g^2 . Consequently the tooth of the dog $a\ b$ 60 is in engagement with the scape-wheel S , and the connection between the latter and the train of the clock motor is established. The detent c is so arranged with respect to the end b of the dog, that when the secondary 65 clock is at the hour, the said end b is quite opposite the said detent.

In the example illustrated, I have made use of a scape-wheel which makes one rotation a minute. Consequently at the end of each 70 minute the end b of the dog is opposite the detent c .

D is a circuit closer, of any suitable construction, but which I have here shown as consisting of a cam-shaped metallic part d 75 mounted on the arbor m of the minute hand, and a part d' in the shape of a spring contact arm. Back of this circuit closer is located a second circuit closer E , consisting of a metallic cam-shaped part e mounted on the arbor m ; a part e' made of insulating material, a portion of which projects above the surface of the part e ; and a contact arm e^2 .

The circuit closer D is intended to close the circuit in case the secondary clock is slow, 85 and to that end is so set, that the circuit is closed by the same at a short time, say two minutes before the hour as indicated by the secondary clock, and then broken at one minute before the hours indicated by said clock. 90 The circuit closer E is intended to close the circuit in case the secondary clock is fast, and to this end it is so set, that the contact arm e^2 leaves the insulated part e' , and consequently closes the circuit at the hour as indicated by 95 said secondary clock and then breaks the circuit shortly after.

The master clock closes the circuit at one minute before the hour, (exact hour,) and breaks it at the exact hour.

It will be readily understood that when the secondary clock is correct, no effect is pro-

duced on the same by the making and breaking of the circuit at the master clock.

Assuming the case that one of the secondary clocks is slow, it will be seen that the circuit is not broken by the circuit closer D, at a minute before the exact hour. Consequently, when the circuit is closed by the master clock at one minute before the exact hour, the electro-magnet M is vitalized and 10 the dog a b is withdrawn from engagement with the scape-wheel S, and the train is free to move until its motion is arrested by the engagement of part b of the dog with the detent c, which takes place at one minute before 15 the hour, and the hands of the secondary clock indicate this time. The circuit is then broken at D and the clock continues in the usual manner.

Assuming the case that one of the secondary 20 clocks is fast,—(the error not to exceed one minute)—it will be seen that the circuit is closed at E at a corresponding time before the exact hour, that is to say, it is closed at the hour as indicated by the secondary clock. 25 The circuit at the master clock being closed at one minute of the hour, as before stated, the dog a b is withdrawn as soon as the secondary clock indicates the hour, but, in view of the fact that at that time the end b of the 30 dog is quite opposite the detent, the train is not permitted to advance, and the clock simply remains idle. The circuit being broken by the master clock at the exact hour, the connection of the train with the scape-wheel is 35 re-established and the clock resumes its motion at that time.

In Fig. 3 I have shown the clocks arranged in a system, A being the master clock; D', its circuit closer; C C' C², the several secondary 40 clocks; B, the battery; 10 and 11, the line wires, and 12, 13 and 14, the several local wires.

Instead of bringing the slow running secondary clock to the correct time at the commencement of the synchronizing period, they 45 may be set slightly in advance of the correct time at this time; then permitted to run in the usual manner, then held until the exact hour, and then released. To this end the circuit closer D, as before, closes the circuit at 50 two minutes before the hour as indicated by the secondary clock, and breaks it at one minute before the hour, but the master clock, instead of closing the circuit at one minute before the exact hour, closes it at, say, sixty-five 55 seconds (more or less) before the hour, so that, as it were, the time at which the master clock closes the circuit overlaps the time during which the circuit closer at the secondary clock is closed. Assuming the case that the secondary 60 clock is correct, it will be seen, that the circuit is closed at D two minutes before the exact hour. The master clock closes the circuit at sixty-five seconds of the exact hour, and consequently the secondary clock is advanced to within one minute of the hour, at 65 which time the circuit is broken at E and the clock again runs as usual, but is actually five

seconds fast. When the secondary clock reaches the hour, as indicated by the same, the circuit closer E closes the circuit and the clock 70 is held at the hour until the circuit is broken at the master clock, at the exact hour. When the secondary clock is slow a like action takes place.

I do not herein wish to restrict myself to 75 any particular means for establishing the connection between the governing member and the train, nor to the application thereof directly to the scape-wheel. Neither do I wish to restrict myself to the duration of the synchronizing periods as here stated, since these will vary with the part of the train to which the connecting device is applied, as well as with the number of times that the clocks are synchronized daily. Neither do I wish to restrict myself to the use of circuit closers, in 80 preference to mechanical means, or to their application to the arbor of the minute hand, as they could be operated by a faster moving part, and brought into action only at the synchronizing period. 85

What I claim as new, and desire to secure by Letters Patent, is—

1. In a clock system, the combination of a master clock constructed to close the circuit 95 at a predetermined period before the hour and to break it at the hour, and a secondary clock provided with a separable connection between two operative parts of the train, an electro-magnet controlling said connection, a 100 detent for arresting the movement of the train when in a predetermined position, and a circuit closer D operated by the train and set to close the circuit through the electro-magnet in advance of the closing of the circuit at the 105 master clock, and to break it simultaneously with the closing of the circuit at the master clock, substantially as described.

2. In a clock system, the combination of a master clock constructed to close the circuit 110 at a predetermined period before the hour and to break it at the hour, and a secondary clock provided with a separable connection between two operative parts of the train, an electro-magnet controlling said connection, a 115 detent for arresting the movement of the train when in a predetermined position and two circuit closers operated by the train; the one being set to close the circuit through the electro-magnet in advance of the closing of the 120 circuit at the master clock, and to break it simultaneously with the closing of the circuit at the master clock; the second circuit closer being set to close the circuit through the electro-magnet at the hour as indicated by the 125 secondary clock, substantially as described.

In testimony that I claim the foregoing as my invention I have signed my name, in presence of two witnesses, this 24th day of June, 1892.

HENRY S. PRENTISS.
